DESIGN FOR A SURGICAL SPOTLIGHT

Jerome Rosenzweig, New York, N. Y., assignor to
Cosmo Sun Ray Products Co. Inc., New York,
N. Y., a corporation of New York

Application July 8, 1943, Serial No. 110,628

Term of patent 14 years

To all whom it may concern:

Be it known that I, Jerome Rosenzweig, a citizen of the United States and a resident of the county of Bronx, city and State of New York, have invented a new, original, and ornamental Design for a Surgical Spotlight, of which the following is a specification, reference being had to the accompanying drawing, forming part hereof, in which:

Figure 1 is a perspective front view of a surgical spotlight, embodying my new design.

Figure 2 is an enlarged fragmentary rear perspective view of the same, the base and a portion of the stand having been omitted for convenience of illustration.

I claim:

The ornamental design for a surgical spotlight, as shown.

JEROME ROSENZWEIG.
